UNITED STATES PATENT OFFICE.

ALVYN RODNA MIESS AND DANIEL E. MIESS, OF COVINA, CALIFORNIA.

GENERATOR FOR LIQUID-FUEL BURNERS.

1,264,322.

Specification of Letters Patent. Patented Apr. 30, 1918.

Application filed July 24, 1917. Serial No. 182,540.

To all whom it may concern:

Be it known that we, ALVYN R. MIESS and DANIEL E. MIESS, citizens of the United States, and both residing at Covina, in the 5 county of Los Angeles, State of California, have invented new and useful Improvements in Generators for Liquid-Fuel Burners, of which the following is a specification.

This invention relates to generators for 10 liquid fuel burners; and relates particularly to means for generating and starting burners which use petroleum distillate or the like for fuel, requiring gasification of the fuel before the burner can start its normal operation. After the burner is in operation the heat from the burner flame serves to thereafter vaporize and gasify the fuel.

It is a particular object of this invention to provide a simple, economical and easily 20 applied means for generating and starting such a burner; and in accomplishing this object we have provided an electrical means of generating the burner, of initially vaporizing and gasifying the fuel. In a burner 25 equipped with a generator according to our invention, the electric current is turned on for a minute or so before the fuel is admitted to the burner. The electric current heats the passages or the retort, through 30 which the fuel passes, to a vaporizing or gasifying temperature; and the fuel, when it is admitted, comes into contact with the heated surfaces and is immediately vaporized and then burned. Once the vapors are 35 ignited, then sufficient heat is had therefrom to keep up the vaporization.

In the following specification we describe several embodiments of our invention, in specific preferred forms; and for this purpose we refer to the accompanying drawings 40 in which—

Figure 1 is a vertical central section of a burner equipped with a preferred form of our invention; Fig. 2 is a reduced plan 45 showing the burner equipped with another form of our invention; Fig. 3 is a central vertical section showing the burner equipped with another form of our invention; and Fig. 4 is a reduced plan showing the same 50 form as shown in Fig. 3.

In the drawings we illustrate our invention as applied to a burner of a particular type. Although we find this type of burner to be particularly efficient, and find our generator to be well combined with this burner; 55 yet it will be understood that we do not

limit our invention to the application of it with this particular type of burner. From the following description it will be readily understood how our generator is applicable 60 to burners of the general class described, and how it may be applied to burners of types different from that particularly herein illustrated.

We illustrate a burner comprising a body 65 10 with a vertical passage 11 leading upwardly through the body. The body 10 is generally cup-shaped and has an outer wall 12 over the upper edge of which the gases and vapors must flow in order to reach the 70 perforated burner ring 13. A cap 14 rests on the ring 13; and this cap 14 has a dependent circular baffle wall 15 under which the gases must flow in order to reach the 75 ring 13; and the cap carries an adjustable 80 deflector 16, adjustable in position over the upper end of the vertical passage 11.

A T-shaped mixing tube 17 fits into the lower end of passage 11, the two opposite 85 ends 18 of the tube 17 being open to atmosphere. A fuel nozzle 19 projects into the mixing tube 17 to project the fuel in a jet into the mixing tube. The fuel is projected up through the passage 11, drawing air 90 through the openings 18, and the mixed air and vaporized fuel pass up against the deflector 16 and then down under the wall 15 and then over the upper edge of the wall 12 and then down next to the ring 13 and through its perforations. Here the mixed air and vapors are burned in a flame extending completely around the burner.

In this preferred form of burner, a retort tube 20 is carried in brackets 21 around the burner. Tube 20 is bent to circular formation and is supported in such a position around the lower part of the burner that it receives just a suitable quantity of heat to properly vaporize the liquid fuel. The liquid fuel enters at 22 and passes around 100 through the retort tube 20 and then (see Fig. 2) passes down through an extension 23 to the member 24 which carries the fuel nozzle 19.

In the usual form of this burner, the tube 105 20 is filled with strands of cable, as illustrated at 25, which causes the liquid fuel to percolate in thin layers through the tube, so as to be more readily heated and vaporized.

In our preferred form of device, as shown 110 in Fig. 1, we interpose a retort 30 between

the part 23 and the nozzle 19. This retort 30 preferably comprises an outer tube 31 containing an inner tube 32 of slightly less diameter. The inner tube 32 is wound with a 5 cable strand 33, and then the expanded ends 34 of the inner tube are brazed or otherwise connected to the ends of the outer tube 31. The tube 23 enters the annular space between the tubes 31 and 32 and the member 10 24 communicates also with this space. The liquid fuel flows into this annular space at one end, and the gases flow out to the nozzle 19 near the other end of the annular space. The nozzle 19 need not connect at the end of 15 the retort; it may connect nearer the center. The space between the nozzle connection and the retort end may become a pressure regulating space. We provide an electric heating element 35, preferably in the form of a 20 coil of resistance wire, within a tube 36 which is slipped into place in the inner tube 32, so as to be easily removable therefrom for substitution or repairs. The tube 36 may be of any suitable electric insulating 25 and heat resisting material; we now use a glass tube. The resistance wires may be led out to connecting wires 37, in any desired manner; we have shown the wires 37 simply being set in plugs 38 of some cementitious material, closing the ends of the 30 tube 36.

Fig. 1 shows an actual construction now in use, showing the parts in approximately full size. We have found that we can generate and start the burner by one and a half 35 minutes previous electrical heating. The current is turned into the coil 35 for about that length of time, and the liquid fuel is then admitted to the retort, passing over the 40 heated surfaces in the retort 30, and being thereby vaporized, so that the vapors may be immediately ignited at the burner ring 13. The current is turned off as soon as the liquid fuel is initially vaporized; and vaporization of the fuel is then carried on in the 45 retort 20.

The foregoing described form of our invention is a simple and convenient one, being simple and inexpensive to manufacture, 50 durable and safe in use, and easy to repair or replace. If the electrical resistance is damaged, the tube 36 may be easily taken out and a new one put in place.

The following described forms of device 55 also embody and illustrate our invention. In Fig. 2 we show a form of device wherein the coil of resistance wire 35^a is inclosed within a tube 36^a and is placed around the exterior of the retort tube 20. For instance, 60 the coil 35^a may be put into an asbestos tube 36^a; and this asbestos tube may be extended along the tube 20, and also along the part 23. This form of device we have found effective.

In Figs. 3 and 4 we illustrate a form of 65 device wherein the coil of resistance wire

35^b is placed within a tube 36^b which is extended around through the interior of the retort tube 20. This interior tube 36^b may be of any suitable electrical insulating and heat resisting material; and the space between the tubes 20 and 36^b may be filled with the cable strands 25. This form of device we have found very effective also.

It will be seen that there are certain fundamental features of our invention which run through all three of the specific forms herein described; that the fuel is heated electrically, by an electrical heating element placed adjacent the fuel retort. Preferably, the heating element is placed within the retort; in such a position it gives greater heating efficiency and is protected against injury. In the particular form of Fig. 1, the straight shape of the heating element facilitates its easy withdrawal for replacement or repairs. The form shown in Fig. 1 is also perhaps more easily manufactured than either of the other two forms.

Having described preferred forms of our invention, we claim:

1. In a device of the character described, an electrically heated retort comprising an outer tubular wall and an inner tubular wall between which the liquid fuel is passed, a resistance inclosing tube removably placed within the inner retort wall, and an electrical resistance in said tube.

2. In a device of the character described, an electrically heated retort embodying a retort tube, a heating element holding tube within the retort tube, and a liquid distributive filling in the space between the two tubes.

3. In a device of the character described, an electrically heated retort embodying a retort tube, a heating element holding tube within the retort tube, and a liquid distributive filling in the space between the two tubes, said liquid distributive filling embodying strands of wire cable.

4. In combination with a liquid fuel burner having a fuel heating retort in which the fuel is normally vaporized by heat from the burner flame, a fuel nozzle through which the vaporized fuel is projected into the 115 burner; a straight retort tube forming a communication between the burner retort and the fuel nozzle, an inner tube within the straight retort tube and attached to its ends, forming an annular fuel vaporizing space, a 120 resistance containing tube within said inner tube, and an electrical resistance therein.

5. In combination with a liquid fuel burner having a fuel heating retort in which the fuel is normally vaporized by heat from the 125 burner flame, a fuel nozzle through which the vaporized fuel is projected into the burner; a straight retort tube forming a communication between the burner retort and the fuel nozzle, an inner tube within the 130

- straight retort tube and attached to its ends, forming an annular fuel vaporizing space, a resistance containing tube within said inner tube, and an electrical resistance therein, the annular fuel vaporizing space being filled with strands of wire cable. 5
6. In combination with a liquid fuel burner having a fuel heating retort in which the fuel is normally vaporized by heat from the burner flame, a fuel nozzle through which the vaporized fuel is projected into the burner; a straight retort tube forming a communication between the burner retort and the fuel nozzle, an inner tube within the straight retort tube and attached to its ends forming an annular fuel vaporizing space, a resistance containing tube within said inner tube, and an electrical resistance therein, the resistance containing tube being of glass and being loosely placed in said inner tube so as to be easily removable therefrom. 10
7. An electric heater for liquids, embodying an outer tube, an inner heating element holding tube, an electrical heating element therein, and there being a liquid passage space between the element holding tube and the outer tube. 25
8. An electric heater for liquids, embodying a tube, a member outside said tube and providing between said member and the tube a thin passage space for liquid, and a removable heating element in the tube. 30
9. An electric heater for liquids, embodying a tube, a member outside said tube and providing between said member and the tube a thin passage space for liquid, a removable element holding tube within said first mentioned tube, and a heating element in said element holding tube. 35
- 40 10. An electric heater for liquids, embodying a tube, a member outside said tube and providing between said member and the tube a thin passage space for liquid, a liquid distributive filling in the said passage space, and a removable heating element in the tube. 45
11. An electric heater for liquids embodying a pair of concentric tubes with a thin liquid passage space between them, a liquid distributive filling in said space, means to introduce and withdraw liquid to and from said space, and a removable heating element within the inner tube. 50
12. An electric heater for liquids embodying a pair of concentric tubes with a thin liquid passage space between them, a liquid distributive filling in said space, means to introduce and withdraw liquid to and from said space, and a removable heating element loosely placed within the inner tube. 55
13. An electric heater for liquids, embodying a pair of concentric tubes with a thin liquid passage space between them, a liquid distributive filling in said space, means to introduce and withdraw liquid to and from said space, one of said means communicating with said space at a point somewhat removed from the end thereof, and a removable heating element within the inner tube. 60
14. An electric heater for liquids, embodying a pair of concentric tubes with a thin liquid passage space between them, a liquid distributive filling in said space, means to introduce and withdraw liquid to and from said space, one of said means communicating with said space at a point somewhat removed from the end thereof, an element holding tube loosely placed within the inner one of the concentric tubes, and a heating element in said element holding tube. 70
- 75
- In witness that we claim the foregoing we have hereunto subscribed our names this 13th day of July 1917. 80
